UNITED STATES PATENT OFFICE.

WILLIAM HENRY SMITH, OF OMEMEE, NORTH DAKOTA.

DESIGN FOR AN ENVELOP-BLANK.

SPECIFICATION forming part of Design No. 28,966, dated July 5, 1898.

Application filed April 29, 1897. Serial No. 634,478. Term of patent 14 years.

To all whom it may concern:

Be it known that I, WILLIAM HENRY SMITH, a citizen of the United States, residing at Omemee, in the county of Bottineau and State of North Dakota, have invented and produced a certain new and original Design for an Envelop-Blank; and I do declare the following to be a full, clear, and exact description of the invention, such as will enable others skilled in the art to which it appertains to make and use the same.

The invention relates to a new and original design for an envelop-blank; and it consists of an envelop-blank of the configuration shown in the accompanying drawing, in which I have represented the blank in plan view.

The leading features of my design consist of a blank having a rectangular body portion 1, laterally-projecting side flaps 2 and 3, the

former of less width than the latter, top and bottom flaps 4 and 5, the former of which has inclined side edges and the latter vertical side edges, said flap 3 having a diagonal slit forming a wing 7, and a line connecting the junction of the lower edge of the flap 6 with the edge of the flap 5 and being at an obtuse angle to the vertical edges of the flap 5 and the horizontal edges of the flap 6.

What I claim is—

The design for an envelop-blank as herein shown and described.

In testimony whereof I hereunto affix my signature in presence of two witnesses.

WILLIAM HENRY SMITH.

Witnesses:
